(57) **CLAIM**

The ornamental design for a wall pack light fixture, as
shown and described.

DESCRIPTION

This application is a continuation reissue application of and
claims priority to U.S. patent application Ser. No. 29/504,
562, filed on Oct. 7, 2014, and titled "Wall Pack Light
Fixture," which is a reissue application of and claims
priority to U.S. patent application Ser. No. 29/406,180, filed
on Nov. 10, 2011, titled "Wall Pack Light Fixture," and
issued as U.S. Pat. No. D668,810 on Oct. 9, 2012, which is
a continuation of and claims priority under 35 U.S.C. §120
to U.S. Design application Ser. No. 29/389,912, titled "Wall
Pack Light Fixture" and filed Apr. 18, 2011, [the] which
issued as U.S. Pat. No. D650,112 on Dec. 6, 2011. The entire
contents of [which] the foregoing applications are hereby
incorporated herein by reference.

More than one reissue application has been filed for the
reissue of U.S. Pat. No. D668,810. In addition to the present
continuation reissue application, U.S. patent application
Ser. No. 29/504,562 is a reissue application of U.S. Pat. No.
D668,810.

FIG. 1 is a perspective view of a wall pack light fixture,
showing my new design;

FIG. 2 is another perspective view thereof;

FIG. 3 is a front view thereof;

FIG. 4 is a left side view thereof;

FIG. 5 is a right side view thereof;

FIG. 6 is a top plan view thereof; and,

FIG. 7 is a bottom plan view thereof.

The broken lines shown represent unclaimed subject matter
and form no part of the claimed design.

1 Claim, 7 Drawing Sheets

**Matter enclosed in heavy brackets [ ] appears in the
original patent but forms no part of this reissue; matter
printed in italics indicates the additions made by reissue.**

Related U.S. Application Data

application for the reissue of Pat. No. Des. 668,810, which is a continuation of application No. 29/389, 912, filed on Apr. 18, 2011, now Pat. No. Des. 650,112.
